(57) CLAIM

The ornamental design for an article of apparel as shown and described.

DESCRIPTION

FIG. 1 is a front perspective view of an article of apparel showing the claimed design;

FIG. 2 is a front elevation view thereof; and,

FIG. 3 is a rear elevation view thereof.

The broken lines in the figures show portions of the article of apparel that form no part of the claimed design.

1 Claim, 3 Drawing Sheets
